UNITED STATES PATENT OFFICE.

JAMES J. MCARDLE, OF PAWTUCKET, RHODE ISLAND.

WINDMILL.

Application filed January 27, 1921. Serial No. 440,523.

To all whom it may concern:

Be it known that I, JAMES J. MCARDLE, a citizen of the United States, residing at Pawtucket, in the county of Providence and State of Rhode Island, have invented new and useful Improvements in Windmills, of which the following is a specification.

This invention relates to certain new and useful improvements in windmills and the primary object thereof is to provide a device of this kind which has novel means for directing an added amount of the wind, and regardless of its direction, onto the propeller buckets or vanes.

The invention further aims to provide a windmill structure wherein the customary and expensive supporting towers are dispensed with, and which accordingly may be of any desired height and supported by guy cables in a manner later set forth.

Still further, the invention aims to provide a windmill which affords maximum of power and has still other and further objects which will be later set forth and manifested in the course of the following description.

In the drawings:—

Figure 1, is a front elevation of the invention;

Figure 2, is a top plan view;

Figure 3, is an enlarged detail view, partly in section of the crown or top bearing;

Figure 4, is a like view of the bottom or base bearing;

Figure 5, is a side elevation, and

Figure 6 is a section on line 6—6 of Figure 5.

In proceeding in accordance with the present invention, a suitable base or foundation structure may be employed and which may be constructed of concrete or masonry, as shown in Figure 1, the bottom of the base being designated 15 and the upper part 16, the latter having a tunnel or passage 22 for the driven belt, not shown.

The windwheel includes a central vertical shaft 5 the lower end of which rotatably engages in a bearing 7 suitably embedded in the base part 15 and may be equipped with ball-bearings 8 and a collar 9 having ball bearings which seat on the bearing 7.

The shaft 5 is provided with a gear 18 which is in mesh with a pinion 19 mounted on a shaft that carries pulley 20, the latter being engaged by a belt (not shown) which

extends through the tunnel 22 and which transmits power to the driven device or the like which the windwheel is to operate.

The windwheel further embodies a series 60 of spaced horizontal wheels having spokes connected by rims 4, the rims having a series of vertical buckets 34 secured thereto, the buckets being disposed in the spaces between the rims, as depicted in Figure 1, 65 of the drawings, and being mounted upon vertical rods 3, which extend through and are connected to the rims.

The upper end of the shaft 5 has a collar 14 suitably secured thereto upon which 70 the lower end of the top or flanged bearing 10 seats, ball bearings 12 being interposed between the upper end face of the shaft 5 and the crown cap or bearing, while vertical roller bearings 13 seat on the upper end 75 of collar, 14 and are interposed between the shaft and the crown bearing or cap 10.

For the purpose of stabilizing the structure, a series of cables 11 are secured to the flanged base of the crown cap 10, and are 80 extended downwardly and suitably anchored to the earth by means of posts secured in a well known manner.

For the purpose of directing an added amount of the wind onto the buckets, a collector is employed which includes side wings 85 24 and 26 having a relatively flaring formation and a hood or cap 25, carried by the wings, the collector being open at its front and rear as shown in Figure 6. Collars 23 90 and 23' are loosely mounted on the shaft 5 below and above the windwheel respectively. Beams 30 are secured to the wings and to Y-shaped castings 42 formed integral with the collars 23 and 23', while a rearwardly 95 extending horizontal beam 27 is connected to the casting 42 and in turn is connected by a diagonal beam 29 to a vertical beam 28, the beams 27, 28 and 29 forming a triangular frame work of which beam 29 is 100 the hypotenuse. The triangular frame work may have its space filled with sail cloth, sheet metal, wood, or any other suitable material and is braced by stay wires 43, the whole forming a vane structure.

For the purpose of supporting the outer end of the triangular vane which said frame work provides so as to allow same to easily and quickly respond to the action of the wind, spaced circular tracks 17 are provided, upon which a pair of castor wheels 38 having rubber tires, ride, the castor

wheels being carried by beam 27. An additional wind collecting hood 40 may be employed and secured to the triangular frame composed of the beams 27, 28 and 29, 5 the purpose of which is to concentrate and direct the wind against tail wings 41 and 42 which latter relatively diverge and are secured to the beam 27.

The feathering buckets as shown in Figure 2 are pivoted at their outer ends to the vertical rods 3 and are tensioned by expansible controlling springs 37 connected to the spokes of the wheel rims 4, rubber buffers or cushions 35 being employed and secured to the wheel spokes so as to engage and cushion the buckets upon the latter being moved by the wind against the spokes.

In operation, the triangular vane, hood 40 and the tail members 41 and 42 are engaged by the wind and move the collector into position for catching the wind regardless of the direction in which the latter may be blowing. The wing engages the buckets on one side of the wheel thereby driving the latter, while the buckets on the opposite side of the wheel feather, the buckets being steadied by the springs in their movements.

What is claimed is:-

1. In a windmill, a vertical shaft, horizontal series of buckets carried by the shaft, a collector extending about the buckets and having side wings and an open front and back, and a cap at its top, a substantially triangular vane extending outwardly from the back of the collector, a curved track for slidably supporting the base of the vane, a collector adjacent to the outer end of the vane, and divergent tail wings, carried by the vane and disposed beyond the rear end 40 of the second collector.

2. In a windmill, a vertical shaft, horizontal series of buckets carried by the shaft, a collector extending about the buckets, and having side wings, and an open front and back, and a cap at its top, a substantially triangular vane extending outwardly from the rear of the collector and divergent tail wings carried by the outer end of the triangular vane.

3. In a windmill, a wheel having a series of horizontal buckets, a collector having opposed side wings disposed about the buckets and having an open front and back, a vane connected to the collector and extending rearwardly thereof and tail wings extending outwardly from the rear end of the vane.

4. In a windmill, a vertical shaft, a wind wheel having buckets carried by the shaft, a triangular vane having a horizontal beam connected to the shaft, an inclined beam and a vertical beam, means to connect the vertical beam to the shaft, a collector having side wings connected to the shaft and disposed about the wheel, a collector carried by the

inclined beam adjacent the outer end of the latter, and tail wings carried by the outer end of the horizontal beam and disposed beyond the second collector.

5. In a windmill, a vertical shaft, a wind wheel having buckets carried by the shaft, a triangular vane having a horizontal beam connected to the shaft, an inclined beam and a vertical beam, means to connect the vertical beam to the shaft, and a collector including side wings connected to the shaft and disposed about the wheel. 75

6. In a windmill, a vertical wind wheel having buckets, a main collector disposed about the wheel, a vane carried by the main collector, and an auxiliary collector carried by the vane. 80

7. In a windmill, a vertical windwheel, a curved top therefor open at its front, and opposite side wings depending from the top to provide a collector in conjunction with the top, the collector being open at its front and rear the front of the top being in approximate register with the front sides of the wings and extending for a spaced distance 90 thereabove, the top being curved rearwardly and downwardly to the upper ends of the wings. 85

8. In a windmill, a windwheel, a collector therefor, a horizontal member connected to the wheel and collector, a vane supported on the member and extending upwardly therefrom, tail wings carried by the outer end of the member, and an auxiliary collector interposed between the tail wings and the first 95 named collector. 100

9. In a windmill, a windwheel, a collector therefor, a vane extending rearwardly from the collector, tail wings carried by the vane and an auxiliary collector interposed between the tail wings and the first named collector. 105

10. In a windmill, a windwheel, a collector therefor, a vane connected to the collector, wings carried by the vane, and means 110 for directing the wind onto and against the wings.

11. In a windmill, a windwheel, buckets carried by the wheel, a collector for the wheel, a triangular vane connected to the collector, wings carried by the rear part of the vane, and an auxiliary collector straddling the inclined side of the vane and arranged to cooperate with the respective opposite sides of the vane to direct wind 120 against the wings. 115

12. In a windmill, a windwheel, buckets carried by the wheel, a collector for the wheel having opposite sides and a hood like top, the top being open at its front and extending above the upper ends of the wings and having its rear extending downwardly and its sides extending toward the sides and connected to the upper ends of the sides. 125

13. In a windmill, upper beams, opposite 130

side wings connected to the beams, a lower beam, a vertical beam connected to the upper beams and to the lower beam for supporting the upper beams from the lower beam, and a wheel having buckets disposed between the side wings and in front of the vertical beam, the rear end of the lower beam

5 and the vertical beam constituting two of the sides of a triangular vane.
